UNITED STATES PATENT OFFICE.

WILLIAM S. MARSHALL, OF WESTCHESTER, PENNSYLVANIA, ASSIGNOR OF ONE-HALF TO GEORGE J. MOSES, OF WESTCHESTER, PENNSYLVANIA.

THILL-COUPING.

SPECIFICATION forming part of Letters Patent No. 739,500, dated September 22, 1903.

Application filed October 21, 1902. Serial No. 128,112. (No model.)

To all whom it may concern:

Be it known that I, WILLIAM S. MARSHALL, a citizen of the United States, residing at Westchester, Chester county, Pennsylvania, have 5 invented certain Improvements in Thill-Couplings, of which the following is a specification.

My invention consists of certain improvements in that form of thill-couplings in which the coupling and securing means are carried 10 directly by the bolt, which passes through the ears or clips of the shackle and the thill-eye.

My invention is fully illustrated in the accompanying drawings, in which—

Figure 1 is a perspective view of my improved form of thill-coupling. Fig. 2 is a sectional view taken on the line *a a*, Fig. 1; and Fig. 3 is a perspective view of the bolt, showing a detail of my invention.

In Fig. 1, 1 represents the axle and cap-piece, to which is attached in the usual manner the shackle 2, carrying the ears or clips 3, between which ears or clips the thill-eye 4 is held. To secure these parts in position, a bolt 5 is employed, which bolt is provided 25 with an eye 6 at one end, and pivoted to this end by means of the pin 7, which passes through said eye, is a bracket 8. This bracket has a depending cup-like portion 9, provided with a recess 10 to receive a plunger 11, having 30 a concaved head 12, adapted to engage the under face of the thill-eye, as clearly shown in Fig. 2, being upheld by a spring 13. This plunger is hollow to contain said spring, and to prevent the dislodgement of the plunger when the coupling is released a screw 14 is employed, which passes through the shell of the depending portion 9 and enters a slot 35 15 in the shell of the plunger.

At the opposite end of the bracket 8 a lever 40 16 is pivoted at 17, and this lever carries a yoke 18, pivoted at 19 and adapted to engage the end of the bolt. The bolt is notched at 20, and this notch has a cam-face 21. The yoke is also provided with a cam-face 22 to 45 engage the cam-face of the bolt-notch, and when these parts are in the locked position, as shown in Figs. 1 and 2, the cam-face of the yoke acts on the cam-face of the bolt-notch and tends to draw said bolt up, so as to make 50 a tight fit. The movement of the lever to lock the parts in place brings the yoke-pivot

in advance of the lever-pivot, so that said lever is thereby retained, and to lock the lever in this position the end of the same is extended and forms a spring-arm 25, with a 55 projection 26, adapted to engage a recess 27, formed in the under surface of the cup-like member 9.

To retain the coupling in place and prevent movement of the same with respect to the 60 shaft and thill-eye, the bolt 5 is provided with a tapering V-shaped projection 28 at one end of the same, adapted to enter a recess 29, formed in one of the ears or clips of the shackle. This projection is made tapering 65 V-shaped, so that the recess with which it engages may be formed with an ordinary three-cornered file.

Having thus described my invention, I claim and desire to secure by Letters Patent— 70

1. In a thill-coupling, the combination of the shackle and thill-eye, a bolt connecting the same, a bracket carried by the bolt, a plunger carried by said bracket and adapted to engage the thill-eye, a yoke adapted to engage the end of the bolt, and a lever pivoted to the bracket and carrying said yoke, said lever adapted to lock the yoke to the bolt and thereby hold the plunger to the thill-eye. 75

2. In a thill-coupling, the combination of 80 the shackle and thill-eye, a bolt connecting the same, a bracket carried by the bolt, and having a cup-like portion; a plunger arranged within said cup-like portion, said plunger having a concaved portion adapted to engage 85 the thill-eye, a spring interposed between said plunger and the cup-like portion of the bracket, a pivoted yoke engaging the end of the bolt, and a lever pivoted to the bracket and carrying the yoke, said lever adapted to 90 lock the yoke to the bolt, and thereby hold the plunger to the thill-eye.

3. In a thill-coupling, the combination of 95 the shackle and thill-eye, a bolt connecting the same, a bracket carried by the bolt, and having a cup-like portion, a plunger arranged within said cup-like portion, said plunger having a concaved portion adapted to engage the thill-eye, a spring interposed between 100 said plunger and the cup-like portion of the bracket, a pivoted yoke engaging the end of the bolt, the latter being notched and hav-

ing a cam-surface, and the yoke having a cam-surface to engage the cam-surface of the bolt, and a lever pivoted to the bracket and carrying the yoke, said lever adapted to lock the 5 yoke to the bolt and thereby hold the plunger to the thill-eye and draw the parts of the coupling tightly in place.

4. In a thill-coupling, the combination of the shackle and thill-eye, a bolt connecting 10 the same and carrying the coupling connection, said coupling having clips or ears through which the bolt is passed, and a tapering V-shaped projection carried by the bolt at its pivotal end, one of the ears of the shackle 15 having a similarly-shaped recess for the reception of the projection carried by the bolt.

5. In a thill-coupling, the combination of the shackle and thill-eye, a bolt connecting

the same, a bracket carried by the bolt, a plunger carried by the bracket and adapted 20 to engage the thill-eye, a yoke adapted to engage the end of the bolt, and a lever pivoted to the bracket and carrying the yoke, said lever adapted to lock the yoke to the bolt and thereby hold the plunger to the thill-eye, said 25 lever having a spring extension with a projection adapted to engage the under side of the cup-like portion.

In testimony whereof I have signed my name to this specification in the presence of 30 two subscribing witnesses.

WM. S. MARSHALL.
